DISPENSING CONTAINER

Frank A. Marx, Bridgetown, Ohio, assignor, by mesne assignments, to Morton Salt Company, Chicago, Ill., a corporation of Illinois

Application June 23, 1953, Serial No. 363,494

2 Claims. (Cl. 222—370)

My present invention relates generally to containers and more particularly to containers for dispensing tableted articles such as pills or the like.

Past practice in the handling of tableted articles has resorted to shipping such tablets in cartons from which they are later emptied into vending or dispensing machines. Such a system entails expensive handling and the exposing of the tablets to contaminating influences. Another system presently employed, and which is much to be preferred over the former, is that of shipping such tablets in a combined dispenser and container whereby such container may serve directly the combined function of shipping carton and dispensing machine. Such a class of combined shipping carton and dispensing machines are presently known, but my invention seeks to improve on such devices bringing forth a dispensing container having improved features of construction and simplicity of operation.

The primary object of my invention is to provide a new and improved dispensing container which doubles as a shipping carton and a dispensing mechanism whereby tableted units or articles may be shipped and dispensed with a minimum of handling.

Another object of my present invention is to provide a dispensing container which has means integrally associated therewith for the dispensing of tableted articles carried within its interior, one at a time, according to the convenience and dictates of the user.

Still another object of my invention is to provide a new and improved dispensing container which is advantageous over such devices heretofore known; both as to its construction and operational characteristics.

The above and further objects, features and advantages of my improved dispensing container will be recognized by those familiar with the art both from the following detailed description and specifications thereof and with reference to the accompanying drawings wherein a preferred form of its features is illustrated.

In the drawings:

Figure 1 is a plan view showing the lay out of a carton blank which goes to comprise the wall portions of my improved dispensing container;

Figure 2 is a perspective view illustrating the dispensing container formed from the assembled blank of Figure 1;

Figure 3 is a longitudinal cross-sectional view taken substantially along lines 3—3 of Figure 2; and

Figure 4 is a cross-sectional view taken substantially along lines 4—4 of Figure 3, such illustrating the construction and details of my improved dispensing apparatus associated with the carton blank of Figure 1.

Turning now to my features of my improved dispensing container, inspection will first be made of Figure 1 of the drawings wherein the lay-out blank 10 for forming the carton portion of my container 11 is illustrated. As will be recognized the blank 10 is made of a suitable material having a requisite stiffness, such as a heavy cardboard or the like for cheapness' sake, and includes a rectangular

2

front wall portion 12 having a square top wall portion 13 attached at fold 14 to one end thereof and a substantially square bottom wall portion 15 likewise attached thereto at fold 16. Attached to opposite sides of wall 12 by folds 17 and 18, respectively, are an inner side wall portion 19 and an outer side wall portion 20; such two side wall portions being of rectangular size and shape conforming with the front wall portion 12. At fold 21 inner side wall portion 19 is joined to a like sized inner back wall portion 22 while at fold 23 side wall portion 20 is adjoined to a similar exterior back wall portion 24. The back wall portion 24 is further adjoined at fold 25 to an outside side wall portion 26, while the inner back wall 22 is similarly adjoined to a retaining flap member 27 at fold 28.

Two similar upper tab members 30, 30 are adjoined one to the upper end of each the inner side wall 19 and the outer side wall 20 at folds 31, 31. Such tab members each cover substantially one-half the size of top wall 13. At the opposite end of the inner and outer side wall portions 19 and 20, two lower tab members 32, 32 are provided; one adjoining to each the inner and outer side walls at folds 33, 33.

The inside back wall portion 22 is adjoined at folds 34 and 35 respectively, to an inside top wall 36 and an inside bottom wall 37.

As will be appreciated from a further study of Figure 1 of the drawings the back wall portion 24 is configured with a substantially rectangular cut-out or opening 40 adjacent its lower edge, while each of the tab members 32, 32 is cut-out at one corner in quadrant fashion as at 41. The inside bottom wall 37 is provided with a substantially semi-circular cut-out 42 along its lower edge. A dispenser operating aperture 43 formed at the junction of bottom wall 15 and the front wall 12 comprises a substantially semi-circular portion intercommunicating with a rectangular portion; the purpose of which opening will be understood more fully from descriptive matter which appears later herein.

From a study of Figures 2 and 3 of the drawings, it will be recognized that the forming blank 10 illustrated, is folded into the shape of a rectanguloid or box-like container with the tab members 30, 30 and inside top wall 36 being folded inside or beneath the top wall 13. Similarly the tab members 32, 32 and inside bottom wall 37 are folded inwardly or inside of the bottom wall 15. In this regard it will be appreciated that when such lower tab members 32, 32 are folded into position the quadrant circular cut-out portions 41, 41 in one corner thereof mate to form a semi-circular opening aligned in substantially concentric relation with the semi-circular cut-out portion 42 of the inside bottom wall 37 and the similarly shaped portion of the dispenser operating opening 43 thus forming an opening through the bottom of the carton. Further, it will be understood that the outside side wall 26 is folded coextensively outward of the inside side wall 19. Likewise inside back wall 22 fits coextensively behind or inwardly of back wall 24.

Means for securing the several walls in their assembled relation comprise any known adhesive applied intermediate the adjacent faces of the outside side wall 26 and the inside side wall 19 as well as intermediate the retaining flap 27 and the adjacent inside face of the outside side wall 26. Tabs 36, 30; inside top wall 36 and outside top wall 13 are retained in their assembled relation by means of a suitable adhesive after the container has been filled with a plurality of tableted units such as 45, 45, indicated in Figure 3. The bottom wall structure of the assembled carton is likewise formulated by gluing the inside bottom wall 37 to underlying tabs 32, 32 and then the outside bottom wall 15 to the underlying wall 37.

Thus it will be recognized that when the carton blank

10 is assembled along its various folds and the several elemental portions thereof related in the manner indicated hereinabove, the rearward wall of the container, indicated generally at 46 in Figure 3 comprises a double wall consisting of the inside back wall 22 and the outside back wall 24. Such two wall members are not cemented together, but are left free with respect to one another so that a plate like bracket element 47 may be slipped in between such two back walls and fastened at its lower end to a suitable supporting surface by screw members 48. In this regard the substantially rectangular shaped cut-out portion 40 at the lower edge of outside back wall 24 assists to clear the screw members 48 when the container of my invention is mounted on the mounting plate 47.

Also to be noted is the dispenser operating opening 43 which is formed intermediate the front and bottom walls 12 and 15, respectively. In the finally assembled carton such opening communicates with the interior of the container adjacent the bottom end thereof and provides means for the passage of tablets from the box as dictated by the operation of the dispensing apparatus, as will now be set forth.

As will be best recognized from an examination of Figure 4, a dispenser means indicated generally at 50, comprises a substantially square shaped base member 51 of dimensions commensurate with the interior dimensions of the assembled container or carton illustrated. One edge of base 51 is formed with a semi-circular opening or indentation 52 for registration with opening 42 of inside bottom wall 37. The dispenser likewise includes a front wall portion 53 having a cut-out suitable for clearing a protruding portion of a dispenser wheel 54. The front wall 53 adjoins to a trapezoidal or substantially triangular shaped upper wall portion 55 (see Figure 4), composed of two layers of material folded together.

The dispensing wheel 54 comprises a circular disc having a plurality of suitably shaped and sized openings 56, 56 conforming to the shape and size of the pill or tablet members 45. Any suitable material, such as plastic or the like, is ideally suited for the manufacture of the dispensing wheel 11 although other materials may be utilized for this purpose as well. In the particular dispensing wheel illustrated, the same is provided with six openings 56 for receiving tablets 45; such wheel being mounted on rivet 57 at its center and in between wall 55 and base 51 so that its periphery extends through the opening in front wall 53.

As will be obvious from an inspection of Figures 2 and 3 of the drawings, the dispensing unit 50 is arranged for insertion as a unit in the lower interior of the container formed from blank 10 with the dispensing wheel 54 protruding through dispensing opening 43 and outwardly of front wall 12 for manual engagement. Additionally it will be appreciated that the semi-circular cut-outs 41, 41, 42 and 43 formulated in the tabs 32, bottom wall 37 and a portion of the dispenser opening 43 respectively, provides an opening for the passage of tablets which is in registry with the path of openings 56 of the dispensing wheel; the latter being capable of carrying a tablet from within the interior of the container to the exterior thereof by rotation of wheel 54 about rivet member 57 and in either direction of rotation as desired.

Having thus described the elements and their mode of combination required for the new and improved container of my invention, it will be understood that with carton forming blank 10 folded as indicated hereinabove, a cheap and light weighted container is provided which is readily adapted for the storage of a given number of unitary articles, such as salt tablets and the like. The disposition of the dispensing wheel 54 adjacent the lower bottom wall of the container obviates the need for any means other than gravity for feeding the tablets 45 to

the dispensing apparatus. In this regard it will be understood that the tablets within the container's interior fall into individual openings 56 of the dispensing wheel and are carried, one at a time, intermediate the wall portions 51 and 55 of the dispenser unit until the same register above the semi-circular cut-out formed in the bottom wall of the container, as described. When such occurs, the tablets fall downwardly by gravity to the hand of the user.

Of outstanding improvement and importance in the container herein described is the formulation of the container's double back wall 46 which facilitates the rapid and convenient mounting of the container on the mounting plate 47. Additionally the protruding disposition of the dispensing wheel 54 so that the periphery thereof extends outwardly of the container's front wall 12 makes for added convenience and operational efficiency to the user. For example, as the user manipulates the dispenser with his thumb the palm of the associated hand will be normally or naturally positioned below the bottom wall 15 for receiving the tablets as they gravitationally discharge from the dispensing wheel openings 56 in which they are carried.

Therefore, while I have herein shown and described the features and improvements of my invention as associated with a preferred embodiment thereof, it will be appreciated that numerous changes, modifications and substitutions of equivalents may be resorted to without departing from the spirit and scope of my invention. As a consequence, I do not wish to be limited for the particular form of my invention herein illustrated and described, except as may appear in the following appended claims.

I claim:

1. A combined dispenser-container of the class described, comprising, a folded carton enclosing a chamber for holding articles to be dispensed, a removable dispensing means insertable as a unit within said carton in a position coextensively paralleling the bottom wall thereof, said dispensing means comprising, a rotatable wheel having spaced article receiving openings formed therethrough, a pair of spaced wall members disposed over opposite faces of said wheel and interjoined along one edge outwardly of said wheel and an axle member fixed transversely between said spaced wall members for rotatably supporting said wheel; said dispensing means being positioned within said carton so as to rest on the bottom wall of the latter and in a manner such that a portion of its said wheel member projects through an elongated opening formed in one side wall of said carton thereby being manually accessible, the said article receiving openings in said wheel passing over a discharge opening formed in the bottom wall of said carton as said wheel is rotatably moved, thereby providing for the gravitational discharge of said articles through said carton's bottom wall.

2. A combined dispenser-container of the class described, comprising, a folded paper carton, said carton enclosing a chamber for holding articles to be dispensed, a unitary dispensing unit mounted within said carton in adjacent parallelism with the bottom wall thereof, said dispensing unit comprising a rotatable wheel having arcuately spaced article receiving openings, a pair of spaced wall members disposed adjacent opposite faces of said wheel and interjoined by a third wall traversing said wheel substantially in chordal fashion therewith, and an axle member fixed transversely between said spaced wall members for rotatably supporting said wheel; said dispensing unit being so positioned and arranged within said carton as to have its wheel member extending transversely outward of one wall of said carton for manual engagement by the user with the path of movement of said article receiving openings in said wheel intersecting a discharge opening formed through the bottom wall of said carton whereby articles carried by said wheel are gravitationally discharged through said carton's bottom

wall when the same are indexed over said opening in the
bottom wall of the latter.
